BELT BUCKLE

Filed Feb. 16, 1929

Fig. 1

UNITED STATES PATENT OFFICE

GEORGE R. BLICKHAHN, OF CHICAGO, ILLINOIS

BELT BUCKLE

Application filed February 16, 1929. Serial No. 340,456.

This invention relates to belt buckles and more particularly to a novel type of belt buckle designed and adapted to inclose a small photograph for which it serves as a miniature frame or mount.

Another object of the invention is to provide an improved belt buckle of the type indicated with means permitting the ready insertion and removal of the photograph, when desired.

Other objects and advantages of the construction and method employed will appear more fully in the details hereinafter set forth, reference being had to the accompanying drawings in which,—

Fig. 1 is a perspective view of a belt to which my belt buckle has been applied;

Fig. 2 is an enlarged sectional view of the construction shown in Fig. 1, certain parts being shown in elevation;

Fig. 3 is a front elevation of my novel belt buckle;

Fig. 4 is a rear elevation of the device shown in Fig. 3;

Fig. 5 is a plan view of the photograph retaining plate, the photograph being removed;

Fig. 6 is a rear view of a modified form of my invention; and

Fig. 7 is a transverse section taken on line 7—7 of Fig. 6.

In the drawings wherein similar characters of reference indicate corresponding parts in the several views of the preferred form of my invention, A designates a belt which may be of conventional design, to which the belt buckle which forms the object of my invention is secured.

The belt buckle B comprises a miniature frame 11 formed of a sheet of metal and having an opening or window 12, the opening being closed by a sheet of transparent material, such as isinglass 13, which serves as a protection for a miniature photograph or snapshot 14, the latter being received in a countersunk portion 15' of a plate 15. The overlapping edges 16 of the frame 11 are clampingly engaged with the plate 15 thereby serving to retain the latter and consequently the photograph or picture and the

transparent material securely in position. When desired, the edges 16 may be bent back and the plate, photograph and transparent material removed for the insertion of a miniature photograph or picture of a different design.

The manner of securing my belt buckle to the belt, is best shown in Fig. 2 wherein the leather thong 17 of the belt A is passed through a yoke member 18 having ears 19 retained in sockets 20 integrally formed in the bent over flanges 21, 22 of the face plate 11, the end of the thong 17 being provided with the usual snap fasteners 23, 24 which provide a means of readily permitting the disengagement of the buckle when desired.

In Figs. 6 and 7 I have illustrated a modified form of my invention. The belt buckle C illustrated in Figs. 6 and 7 comprises a frame 25 having an opening or window 26 closed by a sheet of transparent material 27 behind which a photograph may be placed and secured by the removable plate 28, the latter having a countersunk portion 28' to receive a photograph or picture, similar to that shown in Fig. 5. The means for permitting quick disengagement of the plate 28 with the photograph and the transparent material consists of integral hinge members 29, through which a pintle 30 is passed, the latter also passing through ears 31 provided on longitudinally extending strips 32, these strips, as shown in Figs. 6 and 7 clampingly engaging the plate 28. Springs 33, 34 attached to the pintle 30 have projecting ends 35 which impinge against the strips 32, in this manner a resilient pressing action being maintained on the strips which will serve to securely maintain the plate 28 and consequently the miniature photograph in the frame. To remove the photograph in the modified form of the invention, as shown in Figs. 6 and 7, it will merely be necessary to press back the strips 32 with the fingers, after which plate 28 and the photograph therein

may be removed.

It will, of course, be understood that modification and change may be made in the device as described and illustrated; hence I do not desire to be limited to the precise details

of construction save to the extent these are circumscribed within the limits of the appended claim.

What I claim as new and desire to secure by Letters Patent is:

Insignia holding means for a buckle having a main face plate provided with a window opening, comprising integral hinge supporting members mounted upon said face plate upon opposite sides of said opening, pintle members supported in said supporting members on opposite sides of said opening, a pair of longitudinally extending strips having ear members pivotally mounted upon said pintle members, and a coil spring surrounding each pintle member for normally maintaining said strips in contacting relation with a supported insignia.

In testimony whereof I have signed my name to this specification.

GEORGE R. BLICKHAHN.
